UNITED STATES PATENT OFFICE.

ABRAM C. MOTT, OF PHILADELPHIA, PENNSYLVANIA.

HOT-AIR FURNACE.

No. 873,449.

Specification of Letters Patent.

Patented Dec. 10, 1907.

Application filed May 26, 1905. Serial No. 262,444.

To all whom it may concern:

Be it known that I, ABRAM C. MOTT, a citizen of the United States, residing in Philadelphia, Pennsylvania, have invented certain 5 Improvements in Hot-Air Furnaces, of which the following is a specification.

The object of my invention is to provide a hot air furnace with adjustable partitions, so that vertical chambers can be formed of different area, the chambers communicating with pipes of different area so that a more even distribution of the heat throughout a building is attained than where partitions are not used.

15 In the accompanying drawings: Figure 1, is a view in elevation illustrating my improved hot air furnace, the casing being in section; Fig. 2, is a vertical sectional view on the line 2—2, Fig. 3; Fig. 3, is a sectional plan view 20 on the line 3—3, Fig. 1; and Fig. 4, is a detached view of one of the partitions.

A is the base of the furnace, B is the outer shell made in any number of sections desired, B', in the present instance, is the cast metal 25 front plate on which is hung the ash pit door b, the fire door b' and the drum door b².

C is the top of the furnace having the openings c for the escape of hot air from the furnace. The top plate is flanged so that the 30 hot air conducting pipes D can be properly attached.

It will be noticed, in the drawings, referring to Figs. 1 and 3, that the conducting pipes D are of different diameters, the object 35 being to more evenly distribute the heat throughout a building, this is done by calculating the number of square feet in the different rooms and then connecting the heater with the rooms in such a manner that the 40 large supply pipes will communicate with the larger rooms and the smaller pipes with those of less area.

E is the fire pot of the furnace, E' is the ash pipe and E² is the combustion chamber.

45 F is the drum section mounted above the combustion chamber in any suitable manner, and this drum section consists of a central portion f directly above the fire and a ring f' mounted midway between the outer casing 50 B and the central portion f, so as to form two passage-ways a and a' for the air to be heated, one passage-way between the outer casing and the ring f' and the other passage-way between the ring portion f' and the central 55 portion f.

Heretofore in this type of furnace, partitions were not used, the air would simply pass up through the air spaces and out through one or more of the conducting pipes D, according to the arrangement of the dampers in 60 the pipes, but in many cases some of the pipes would receive more hot air than others and the rooms would not be evenly heated.

By my invention, I need not necessarily alter the construction of the furnace, but 65 simply add vertical partition plates I which extend from the base of the fire pot in the present instance to the top plate C of the furnace. These partition plates I are made in two pieces i, i', as clearly shown in Fig. 4. 70 The piece i is slotted at i² so as to pass over the ring section f' of the heating drum F and it is secured to the lower part i' by a line of rivets or bolts as at i³. The lower part i' is shaped to conform to the fire pot E and combustion chamber E². It is rigidly held from vertical movement but is free to be adjusted laterally to any position, so that when the furnace is assembled any number of partitions may be mounted in place, for instance, 80 eight partitions are shown and these partitions can be adjusted by the furnace man after the area of each room is taken, so that the large conducting pipes which communicate with the large rooms will communicate with 85 a larger heating space than those communicating with small rooms, and this is done by shifting the partitions, as for instance as indicated in Fig. 3.

The partition plates I are shown as terminating at the base of the fire pot but in some instances, they may terminate either above or below this point without departing from my invention.

By my invention I am enabled to construct 90 furnaces of this type in large numbers and the partitions can be readily shifted by the man who places the furnace in position without having to design a furnace for each particular building.

100 My invention can also be applied to furnaces now in existence by simply providing the vertical partitions, as shown in Fig. 4, allowing the furnace man to apply the partitions as desired.

I claim as my invention:

The combination in a hot air furnace, of an outer casing, a fire pot, a combustion chamber and a heating drum all mounted within the outer casing, said heating drum having a 110

ring section forming two passage-ways for the air to be heated, a series of vertical partitions extending from the base of the fire pot to the top of the outer casing, each vertical 5 partition being made in two parts, the upper part being slotted so as to pass over the ring section of the heating drum, the lower part being shaped to fit the fire pot and combustion chamber and secured to the upper part, 10 the casing having flue openings connected to

the several sections separated by the vertical partitions, substantially as described.

In testimony whereof, I have signed my name to this specification, in the presence of two subscribing witnesses.

ABRAM C. MOTT.
